(57) **CLAIM**

The ornamental design for a dispenser, as shown and described.

DESCRIPTION

FIG. 1 is front perspective view of a dispenser with a lid closed showing a first embodiment of our new design.

FIG. 2 is a front perspective view of the dispenser with the lid open.

FIG. 3 is a side view thereof.

FIG. 4 is a front view thereof.

FIG. 5 is a rear view thereof; and,

FIG. 6 is a top plan view thereof.

No bottom view is presented as the bottom is unornamented and does not form a part of the design.
